UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK.

LOOSE-LEAF BINDER.

Application filed June 16, 1922. Serial No. 568,687.

To all whom it may concern:

Be it known that I, CLARENCE D. TRUSSELL, a citizen of the United States of America, residing in Poughkeepsie, in the 5 county of Dutchess and State of New York, have invented certain new and useful Improvements in Loose-Leaf Binders, of which the following is a specification.

This invention relates to loose-leaf binders of the ring type, in which the loose leaves are impaled on half rings or hooks mounted on back plates or other mounting, whereby they may be opened or closed at will, the usual and preferable construction being one 10 whereby spring pressure is applied to press the half rings together when closed, or hold them apart when opened.

The particular feature to which the present invention is directed is aligning means 15 engaging the inner edges of the sheets within the hooks, so as to hold the perforations in the sheets (which are made larger than the hooks) pressed outwardly into such close engagement with the hooks as to hold the 20 sheets or leaves firmly when the hooks are closed to form complete rings, and the ring book is laid open. Such aligners, as applied to such loose-leaf books of the ring type, are set forth and claimed broadly in my re- 25 issued Patent No. 15,322, reissued March 28, 1922 (original Patent No. 1,180,342, dated April 25, 1916).

According to the present invention the aligners are made each in two sections, so 30 that when the book is laid open one section engages the leaves or sheets of the right-hand page, and the other those of the left-hand page. A space or gap is formed between them, which gives a better appearance 35 to the book. The aligner sections are made adjustable, so that they may be adapted to leaves or sheets having the perforations punched at varying distances from the inner margin.

40 The improved construction is shown in the accompanying drawing, wherein,—

Figure 1 is a transverse section of the back portion of the book showing one ring and its mounting, the half rings or hooks 45 being closed together to form a complete ring;

Fig. 2 is a fragmentary plan of Fig. 1;

Fig. 3 is a view similar to Fig. 1, but showing only the metal elements and illus-

trating a somewhat different embodiment of 55 the invention;

Fig. 4 is a fragmentary plan of part of Fig. 3, the aligners being in section on the line 4—4;

Fig. 5 is a section showing the attachment 60 for the aligners, taken on the line 5—5 in Fig. 4;

Figs. 6 and 7 show another construction, Fig. 6 being a section on the same plane as Fig. 5, and Fig. 7 being a perspective view of 65 one of the aligner sections.

In Figs. 1 and 2, A is the book cover and B, as a whole, is the loose-leaf binding means applied thereto. The important feature of this binding means is the provision 70 of half rings or hooks C C, which, when closed together, form a substantially complete ring, as shown in Fig. 1, these half rings or hooks being provided with any suitable mounting and any suitable means for 75 holding them in their closed or open positions, these means being according to any of the constructions employed in the ring binder art. A suitable construction is that shown, which includes hook plates D D to 80 which the hooks are attached, the plates being hinged together in any suitable way at their inner edges so as to have a rocking engagement, and engaged at their outer edges within inturned flanges of a spring 85 back plate E, which, by exerting inward pressure against the outer edges of the plates D, D, acts, when the hooks are closed, to press them together, and, when the hooks are opened or separated, to hold them apart, 90 in manner well understood. It is common to provide such binders with a top plate F which covers the hook plates and makes a neat finish, and also serves as a support for the punched or perforated marginal portions 95 of the sheets or leaves. These latter are shown at a a, and their perforations are indicated at b b. Only a fragment of the book is shown, including one ring or pair of half rings or hooks, it being understood that at 100 least two rings, and commonly three or more, are used.

G is the aligner, which, according to the present invention, is preferably fastened to the top plate F, although it might be otherwise mounted. It is desirable to use at least two aligners, and to place these either near the tops and bottoms of the sheets a, or

reasonably near to the end rings. The function of the aligners is to bear against the inner edges or margins of the sheets or leaves and hold them outward, so as to take up the 5 looseness in their perforations (which have to be made somewhat larger than the hooks), whereby when the book is laid open, as shown, the leaves are held firmly in place, so that a person may write upon or otherwise 10 use the leaves without their either shifting around or having to be held in place by hand.

According to the present invention, the aligner G is made essentially of two parts or 15 sections confined respectively to the right and left-hand sides of the binder, as shown, and so as to leave between them a gap or opening α at the top. As the essential function of the aligner is performed only when 20 the book is laid open, and then with respect only to the leaves or sheets lying in substantially flat location to right or left, it is apparent that this function cannot be performed at the top. Heretofore aligners of 25 my invention have been extended over the top in one continuous loop, with a view to utilizing this part of the aligner to guide the sheets in turning over the leaves. That 30 function of the aligner is not availed of in the present construction, by reason of the omission of the top part of the aligner at the gap α .

The aligner is made of sheet metal of sufficient stiffness, and yet of such pliability that 35 it may be adjusted slightly by bending. It may be made in one piece, as shown in Figs. 1 and 2, and fastened by riveting or otherwise to the top plate F. Or it may be made 40 in two separate pieces, as shown in Figs. 3 to 5, and Figs. 6 and 7. In either case the right and left sides or sections of the aligner perform the same function, and in either case these portions may be adjusted by bending to bring them into correct relation with 45 the inner margins of the sheets or leaves. It is desirable that the distance between the outer face of each aligner section, and the inner face of the adjacent hook C, shall, when measured in the planes in which the 50 leaves lie, be exactly equal to the distance between the margin of each leaf and its perforation; when this condition exists the leaves are held firmly when the book is laid open, and yet they are free to turn in running 55 over the pages of the book.

There is no absolute standard in the punching of leaves for ring books, and it may happen that a user having bought a 60 ring binder from one manufacturer, may desire to use it with leaves obtained from a stationer, the punching of which differs slightly from the dimension intended by the manufacturer of the binder; in this case the dimensions above stated with respect to the 65 binder, and the leaf punchings, may not

agree, so that the leaves are held too tightly, so that they tend to wedge in place, or are held so loosely that the function of the aligner is partly lost. In such case with the 70 present improvement the user may bend the half sections of the aligner outwardly or inwardly, so as to vary the dimensions between their outer faces and the inner faces of the hooks, and thereby bring them to a correct fit with the punched sheets or leaves. 75 This function may be more perfectly performed by forming the aligner sections as separate pieces, as shown, for example, in Figs. 3 to 5, where the aligner sections G¹, G² are distinct, each having a base portion lying 80 against the top plate F and clamped or clinched tightly thereto by means of a fastening plate H beneath it, having prongs or ears I, I, passing up through slots J in the top plate F, and clinched down upon the 85 bases of the sections G¹, G², so as to clamp them tightly and immovably in place. When these sections require adjustment they may be tapped outwardly or inwardly, as 90 may be required, or the ears I, I may be partly loosened or slightly turned up to release their engagement with the sections, and after adjustment of the latter may then be driven down again into tight clinching 95 engagement therewith.

To insure sufficient freedom of motion, and particularly when the adjustment of the aligner sections is accomplished solely by bending, it is preferable that the lower portion of each section, abutting the few leaves 100 nearest the side covers of the book, be made a somewhat looser fit with the leaves than the remaining portion. Thus, if the binder is required to be used with leaves punched with a wider margin than those for which 105 the aligner was made, and it is adjusted thereto by bending its sections, the greater space afforded near its junction with the top plate prevents the few leaves nearest the top plate from being jammed between the 110 aligners and the hooks or half rings.

Another construction is shown in Figs. 6 and 7, where the sections (only one of which is shown, lettered G³) are formed with downturned ears K which pass down through 115 slots L in the top plate and are turned or clinched thereunder as shown. This fastening may afford the same adjustment as in Fig. 3, by making the slots L somewhat longer than the width of the ears K; or by 120 making the slots of the same width as the ears, the bases of the sections G³ will be fastened immovably to the same effect as if riveted down.

One advantage of the present construction 125 is that it makes the ring book more attractive in appearance, especially when in use, because the gap or omitted portion α enables the user to look down through to the top plate, which affords the finish, instead of 130

having this view obstructed by the two or more arches formed by the aligners as heretofore constructed. When the book is fairly well filled with leaves and opened to approximately the middle, the aligner sections are not noticeable. It is preferable to incurve the upper edges of the two sections of the aligner as shown at *c*, to prevent the edges of the leaves catching against the edges of the aligner sections in turning over the leaves.

The aligners according to the present invention should be made of sheet-metal of sufficient stiffness to hold its form in use, although this does not exclude the use of sufficiently resilient metal so that the aligners would yield slightly and maintain a constant outward pressure against the margins of the leaves. The invention may be availed of if the aligner sections are either substantially rigid or slightly yielding or elastic.

While the described embodiments of the invention are considered the preferable ones, yet it will be understood that it may be otherwise constructed if desired, within the scope of the appended claims.

I claim as my invention:—

1. In a loose-leaf binder of the ring type, an aligner for the inner margins of the sheets, consisting of two lateral curved portions, with a central gap or opening between them at the top.

2. In a loose-leaf binder of the ring type, an aligner for the inner margins of the sheets, consisting of curved plates fastened at bottom and free at the top, and adapted to be adjusted by bending to vary their relation to the rings.

3. In a loose-leaf binder of the ring type, an aligner for the inner margins of the sheets, consisting of curved plates fastened at bottom and free at the top, and adapted to be adjusted toward or from each other.

4. A loose-leaf binder of the ring type, having an aligner for the inner margins of the sheets, consisting of curved plates fastened at bottom and free at the top, the bottom fastenings adapted to permit them to be adjusted toward or from each other.

5. A loose-leaf binder of the ring type, formed with a top plate, and having an aligner for the inner margins of the sheets consisting of curved plates fastened at bottom to said top plate and free at their tops, and adapted to be adjusted toward or from each other.

6. A loose-leaf binder of the ring type having a top plate, and aligners consisting each of two separate curved plates with their bottom portions fastened adjustably to said top plate.

In witness whereof, I have hereunto signed my name.

CLARENCE D. TRUSSELL.
